(57) **CLAIM**

The ornamental design for a cat litter box set, as shown and described.

DESCRIPTION

FIG. 1 is a perspective view of a cat litter box set showing our new design;

FIG. 2 is an exploded perspective view of the cat litter box set;

FIG. 3 is a perspective view of a first component of the cat litter box set, shown separately for illustration;

FIG. 4 is another perspective view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof;

FIG. 10 is a bottom plan view thereof;

FIG. 11 is an enlarged view of portion 11 shown in FIG. 3;

FIG. 12 is a perspective view of a second component of the cat litter box set, shown separately for illustration;

FIG. 13 is another perspective view thereof;

FIG. 14 is a front elevational view thereof;

FIG. 15 is a rear elevational view thereof;

FIG. 16 is a left side elevational view thereof;

FIG. 17 is a right side elevational view thereof;

FIG. 18 is a top plan view thereof;

FIG. 19 is a bottom plan view thereof;

FIG. 20 is a cross-sectional view taken along the line 20-20 shown in FIG. 18;

FIG. 21 is an enlarged view of portion 21 shown in FIG. 12;

FIG. 22 is an enlarged view of portion 22 shown in FIG. 20; and,

FIG. 23 is a perspective view of the cat litter box set where the cat litter box set is in a configuration of use.

The dash-dash broken lines in the drawings depict environment of the cat litter box set that form no part of the claimed design. The dot-dash broken lines represent boundaries of the enlarged portions and form no part of the claimed design.
